UNITED STATES PATENT OFFICE.

J. W. DURHAM, OF DURHAMVILLE, TENNESSEE.

ENGINE FOR EMPLOYING STEAM OR ANY OTHER AERIFORM OR GASEOUS BODY UNDER PRESSURE TO OBTAIN MOTIVE POWER.

Specification of Letters Patent No. 29,149, dated July 17, 1860.

To all whom it may concern:

Be it known that I, J. W. DURHAM, of Durhamville, in the county of Lauderdale and State of Tennessee, have invented a new 5 and Improved Engine for Employing Steam or any other Aeriform or Gaseous Body Under Pressure to Obtain Motive Power; and I do hereby declare that the following is a full, clear, and exact description of the 10 same, reference being had to the accompanying drawing, forming part of this specification, in which—

Figures 1, and 2, are vertical sections at right angles to each other of my improved 15 engine adapted for the use of steam as the motive agent.

Similar letters of reference indicate corresponding parts in both figures.

My invention consists in an upright endless chain of buckets arranged within a suitable box which is filled with water to a suitable level and to which steam or other gaseous or aeriform body at a pressure greater than the atmosphere is introduced 20 by a pipe or pipes in such a manner as to enter the buckets below the surface of the water and to displace the water therefrom and to give motion to the chain of buckets by its tendency to rise to the surface of the 25 water.

To enable others skilled in the art to make and use my invention I will proceed to describe its construction and operation.

A, is the box made of wood or metal and 30 having suitable bearings in or attached to its sides for two horizontal shafts B, C, arranged one above the other, the lower one B, not projecting through the sides of the box but the upper one C, projecting through 35 one or both sides to carry a driving gear or pulley by which to transmit the power. To each shaft there are attached two chain wheels D, D, having notches at uniform and suitable distances apart to receive the ends 40 of the transverse rods a, a, which connect the links b, b, of the two endless chains to which the buckets E, E, are attached. The buckets are of open box form and so arranged as to present their open sides upward 45 on one side of the chains and downward on the other side as shown in Fig. 1.

F, is a pipe entering the box near the top to supply it with water.

G, is a pipe for the water to flow off from the box when it reaches a certain level above 55 the upper shaft.

H, is a pipe which supplies the steam or other motive agent from the boiler or generator, entering the box near the bottom of that side toward which the buckets present 60 themselves with their mouths downward.

I, is a pipe which is only used when steam or other condensable vapor is used as the motive agent, entering the box near the bottom on the opposite side to H, for the purpose of keeping the water hot while the engine is at rest to enable the engine to be easily started. Another pipe may be used when steam is the motive agent to convey 65 hot water from the box A, to the boiler. 70

J, is an opening in the top of the box for the escape of the steam or other motive agent from the box A, after it has performed its duty.

K, is a stationary block which may be 75 either solid or hollow arranged between the sides of the box within the chains to fill up a portion of the useless space within the box and reduce the necessary quantity of 80 water.

The operation of the engine is as follows: The steam or other motive agent, suppose steam for example, entering the box by the pipe H, at first condenses, but as soon as the water is heated to the boiling point, condensation ceases, and the steam begins to rise toward the surface of the water and in so doing displaces the water from the bucket which is presented with its mouth open in a downward direction over the said pipe H, 85 and fills or partly fills the said bucket and by its continuing to rise lifts the bucket and sets the whole chain of buckets in motion in the direction of the arrows shown in Fig. 1, and every bucket as it is in its turn presented over the mouth of the said pipe is 90 filled in a similar manner and caused to rise and in this way the endless chain of buckets is kept continuously in motion and caused to give rotary motion to the chain wheels 100 E, E, and shaft C, D; and the shaft C, transmits the power developed by the action of 95

the steam to any machinery with which it may be connected. The steam, as fast as the mouths of the buckets arrive above the surface of the water, escapes from them into 5 the upper part of the box A, and from thence by the opening J, to the atmosphere.

This engine possesses many advantages over the ordinary steam engine among which may be mentioned its extreme simplicity of 10 construction, its freedom from friction, the absence of its liability to get out of order and the low pressure which is sufficient to work it.

I do not confine myself to the precise 15 details of construction herein described, as such may be varied or modified without de-

parting from the principle of my invention, but

What I claim as my invention and desire to secure by Letters Patent is—

An engine composed of an endless chain of buckets arranged within a box of water with suitable pipes or other means of ingress or egress to and from the said box the whole being constructed arranged and 25 combined so as to produce an operation substantially as herein described.

J. W. DURHAM.
